ABSTRACT OF THE DISCLOSURE

A reciprocating hook needle shoe lacing machine for inserting cord loops into eyelets and for forming knots between the legs of the loops arranged to retain each loop on a needle from the time the cord forming that loop is laid in that needle hook until a succeeding loop is retracted through that loop. This is accomplished by rotating the needles as they are reciprocated to bring the loops into surrounding relation to the needle shanks while at the lower ends of their reciprocating strokes.

This invention relates to improvements in shoe upper lacing machines, such as disclosed in United States Letters Patent No. 2,056,961, granted Oct. 13, 1936, and No. 2,106,320, granted Jan. 25, 1938, both in the name of 25 the present inventor.

The machine of Patent No. 2,106,320 is effective and commercially successful in lacing eyeleted shoe uppers preparatory to lasting, at the present time, but the machine is expensive to manufacture and requires special skills and abilities in its maintenance and repair because it employs a number of parallel eye needles, each operated to reenter repeatedly into a pair of aligned eyelets and then into previous loops of lacing cords inserted by the needles, thus to enchain the loops with nonslip knots. Unless precisely manufactured and carefully adjusted the needles and other cooperating devices are subject to frequent contingencies tending to misalign them relatively to the eyelets, with the result that parts of the machine may be bent or damaged or the uppers themselves may be pierced outside the eyelets or otherwise rendered unfit for use.

The machine of Patent No. 2,045,961 has never been commercialized for the reason that it was even more prone to faulty operation than that of Patent No. 2,106,320. While the machine of Patent No. 2,056,961 does not require the needles to reenter the eyelets of an upper after once having withdrawn following insertion of initial loops of lacing cord, the machine does depend for an essential part of its operation upon taking each cord loop from a needle and holding it open after its retraction with an excessive amount of slack at a position where the needle may re-enter and be advanced through it without danger of missing or stranding the loop. Holding each loop open with the cord slack for reentry of the needle in this way depends upon previous disengagement of each loop from the needle hook and as a result considerable difficulty is encountered on account of the slack required in the crowded space available in the machine about the point of needle operation, especially because the amount of slack required is not conducive to accurate control of the cord. Thus, both patented machines are more critical in their operations and more sensitive to maladjustments than good manufacturing, operating and servicing economics should warrant.

The primary objects of the invention are to provide a shoe upper lacing machine having none of the defects found in prior machines, as noted above, and otherwise to simplify the construction and mode of operation for shoe upper lacing machines generally without requiring exercise of special skills in manufacture or service and

2

to improve the machine of Patent No. 2,056,961 in particular, in a manner to eliminate the necessity for holding open in slack condition each loop of lacing cord for reentry of the needle as basis for its essential operation. In this way, a simplified and improved construction for a lacing machine has not only been accomplished, but because liability for contingencies interfering with proper operation and tendencies for criticalness and sensitivity to maladjustment have been eliminated, it is possible to decrease the over-all size and weight of the present machine substantially from that of any prior machine of the same type.

To the ends noted, the present machine includes instrumentalities to retract initial loops of lacing cord through superposed eyelets of a folded shoe upper and to form knots between the legs of those loops by en chaining successive additional loops in a manner similar to that employed in the machine of Patent No. 2,056,961 without the necessity of taking slack loops from the needles, the instrumentalities including a number of straight reciprocating hook needles arranged to enter and retract in unison from the eyelets, a clamp being provided for securing the upper during operations, together with a set of loopers for the needles and suitable mechanisms for actuating the needles to enable laying legs of each initial loop alternately into the hook of a needle while that needle also holds under proper tension a previous loop, so as to be free from likelihood of entanglement. The actuating mechanisms are arranged to cause each loop of cord to be retained directly on each needle from the time in which it is laid in the hook of that needle until the cord for the succeeding loop is engaged therewith, a knot comprising a nonslip engagement of en chained loops eventually being reached. In this way the necessity for disengaging each loop from a needle hook and for holding it accurately by the use of an additional hooked instrument in open position for reentry by that needle during a succeeding en chaining stroke, as in the patented machine just referred to, is avoided.

Other features of the invention, as hereinafter described and claimed will readily be understood by those skilled in the art from the following detailed specification taken in connection with the accompanying drawings, in which:

FIG. 1 is a side perspective view, partly broken away and in section, looking from the right of a shoe upper lacing machine embodying the features of the present invention;

FIG. 2 is a front perspective view of the machine illustrated in FIG. 1;

FIG. 3 is a fragmentary side view, partly in section, looking from the left of the machine;

FIG. 4 is a detail side sectional view on an enlarged scale, looking from the right of an individual lacing unit and some of its actuating connections in the machine;

FIG. 5 is a detail view in front elevation of a portion of a cord gripper hook and cutter in the machine;

FIG. 6 is a fragmentary sectional plan view of the cord gripper hook and cutter, taken along the line VI—VI of FIG. 4, showing the positions of the parts with the gripper advanced just before a cord is gripped and severed at the end of a lacing forming operation;

FIG. 7 is a similar sectional view taken after the cord is severed and the end of the cord remaining in the machine is gripped;

FIG. 8 is a detail plan view on a reduced scale of a shoe upper clamp and parts of an actuating mechanism for a looper fork employed in the machine;

FIG. 9 is a detail view in front elevation and partly in section of a supporting slide for the upper clamp shown in FIG. 8, taken along the line IX—IX of that figure;

FIG. 10 is a sectional view showing a latch for lock-

ing one member of the clamp, taken along the line X—X of FIG. 8, showing the clamp in locked position;

FIG. 11 is a partial sectional view in right side elevation of the machine, certain parts having been removed to illustrate the underlying construction;

FIG. 12 is a diagrammatic plan view of successive angular positions assumed by one of a series of hooked lacing needles in the machine, illustrating rotary movement imparted to the needle;

FIG. 13 is a perspective detail view of parts of the machine surrounding one of the lacing needles, illustrating the manner of laying a cord in a needle hook;

FIG. 14 is a similar view, illustrating the needle in an angular position which avoids improper engagement with the lacing cord after having been laid in the needle hook;

FIG. 15 is a detail view in front elevation and on an enlarged scale, partly broken away and contracted in height of portions of two lacing units, showing their spaced relationship and manner of mounting in the machine;

FIG. 16 is a detail plan view of spacing connections for the lacing units;

FIG. 17 is a fragmentary view in side elevation of a shoe upper after having been laced in the machine;

FIG. 18 is a front detail view, partly broken away and in section, of mechanism for actuating measuring fingers to provide essential amounts of cord for each lacing;

FIG. 19 is a detail view in right side elevation, partly broken away and in section, showing looper fork actuating and cord measuring mechanism in the machine;

FIG. 20 is a somewhat enlarged view in front elevation, partly broken away and foreshortened in width, of a portion of the looper actuating mechanism;

FIG. 21 is a view in right side elevation of a portion of the looper actuating mechanism shown in FIG. 20;

FIG. 22 is a further detail view, partly broken away to reduce its width, of other portions of the looper actuating mechanism, shown in section along the line XXII—XXII of FIG. 19;

FIG. 23 is a detail view on a reduced scale of a main cam shaft with its cams and driving train in the machine;

FIG. 24 is an enlarged sectional view in rear elevation of a fork portion of a looper for laying cord in a needle hook;

FIG. 25 is a detail view in right side elevation, on a reduced scale and partly in section, of a cord controlling take-up and its actuating mechanism;

FIG. 26 is a right side detail view on an enlarged scale of a cord tension release device;

FIG. 27 is a detail front view of the cord tension;

FIG. 28 is a sectional detail view in right side elevation and on a reduced scale of mechanism for reciprocating and rotating the needles;

FIG. 29 is a similar view, partly broken away and in section, of mechanism for actuating the cord gripper and cutter and a mounting for a cord measuring finger;

FIG. 30 is an enlarged detail plan view, partly broken away, of a mechanism for measuring cords from individual supplies to enable successive lacings in an upper to be graded in length along the eyeleted edges of an upper;

FIG. 31 is a sectional view of the cord measuring mechanism as seen from the line XXXI—XXXI of FIG. 30;

FIG. 32 is a detail plan view, partly broken away, of a cord measuring bar, illustrating its position when the lacings are to be the same lengths;

FIG. 33 is a detail view in right side elevation of a cord positioning bar and its support member mounted on the frame of the machine;

FIG. 34 is a detail view in front elevation of the cord positioning bar and its support member;

FIG. 35 is a sectional view in right side elevation on a reduced scale of the front portion of the machine, parts being broken away and shown in section to illustrate the

operation of the machine on a folded shoe upper whose superposed eyelets are impaled on the needles;

FIG. 36 is a detail view in front elevation of a needle and looper illustrating the initial manner of laying a cord in the hook of a needle;

FIG. 37 is a view similar to that of FIG. 35 but showing the formation of the initial loop of cord passing through the pair of superposed eyelets by a needle;

FIG. 38 is a detail view in front elevation, showing a connection to the looper fork employed as an alternative in laying the lacing cord in the hook of a needle;

FIG. 39 is a detail view, in right side elevation, similar to that of FIG. 37, but showing the alternative looping operation of FIG. 38 in a more advanced stage;

FIG. 40 is a similar view, showing the second loop of cord being retracted through the initial one;

FIG. 41 is a similar view, showing the manner of progressively tightening a knot being formed after the second cord loop has been drawn through the initial one;

FIG. 42 is a similar view, showing the angular position of the needle preparatory to the formation of the third cord loop in a lacing;

FIG. 43 is a similar view, illustrating the position of the needle, at which the cord is laid in the needle hook for the third time in a lacing cycle;

FIG. 44 shows the formation of the third loop of cord in a lacing, the needle retracting it through the second loop;

FIG. 45 is a view showing the tightening action of the needle and the cord gripper on the third cord loop;

FIG. 46 shows the alternative operation of the looper in laying the cord in the hook of the needle preparatory to the formation of the fourth cord loop;

FIG. 47 is a view showing the needle in its last reciprocation while forming the fourth and final cord loop, a cord gripper hook reaching forwardly to engage the cord between the lacing being formed and the cord supply and releasing the free end of the lacing just formed;

FIG. 48 is a similar view showing the cord gripper hook moved rearwardly to sever the cord between the lacing being formed and the supply and to grip the end of the cord remaining in the machine, the needle having ascended to release the final cord loop from its hook;

FIG. 49 is an enlarged sectional view taken through a pair of laced eyelets in an upper, showing the nature of the lacing;

FIG. 50 is a fragmentary view of a laced upper with the knot in a lacing loosened for a better understanding of the knot formation;

FIG. 51 is a sectional detail view, looking from the front of the machine and showing portions of the clamp for gripping the upper, a pair of latches for locking the clamp in lacing position, and a pair of microswitches for starting the machine in operation when the clamp grips the upper;

FIG. 52 is a wiring diagram of a starting circuit controlled by the microswitches shown in FIG. 51; and

FIG. 53 is a time chart of the movements imparted to the lace forming the knot tying instrumentalities in the machine by the cams shown in FIG. 23.

The machine disclosed herein is intended to form loops and tie knots in a series of lacings passing through several superimposed pairs of eyelets in a folded shoe upper, so that the upper may be lasted without undue displacement of its sides along the surface of a last when a conforming pull is applied to the upper. Briefly, the upper to be laced is gripped by a set of clamp members in a position determined by a series of reciprocating straight hook needles, each acting in unison with the others to insert an initial loop of lacing cord in each pair of eyelets, to carry the loop across the edges of the upper, to tie a knot between the legs of each initial loop and the bight of that loop, to tighten each knot and finally to sever the completed lacings from sources of cord supply in the machine after the lacing is completed. For con-

venience, each knot is composed of four successively en-chained loops, an initial one and three additional ones, to afford a nonslippling engagement. Acting with the needles are loopers and other essential instrumentalities.

To enable the lacings to be inserted in uppers having differently spaced eyelets all of the instrumentalities are mounted upon a series of individually shiftable units ar-ranged to move toward and away from each other through the interaction of spacing connections.

The nature of the lacings is illustrated in FIG. 50 of the drawings, which shows a main initial loop 1 in a cord inserted in a pair of eyelets 3 in the edges of a folded shoe upper 5. Each leg of an initial loop 1 is formed suc-cessively into additional loops 7, 9 and 11, the second loop 7 being passed through the bight of the initial loop 1, the third loop 9 being passed through the bight of the second loop 7 and the fourth loop 11 being passed through the bight of the third loop 9, each acting to lock the previously inserted loop in place. To secure the knot each locking loop is tightened after being passed through the previous loop rather than being left loose, as shown for clarity of illustration.

Before starting the machine in operation the eyelets at opposite sides are superposed and the lacing units are shifted to aline the needles with superposed pairs of eyelets, the eyelets are impaled by the needles and the clamp members are actuated to prevent escape of the upper from the needles. As soon as the clamp members are actuated the machine is started. When the machine starts the clamp members are actuated further to grip the upper securely in folded condition assumed in impaling the eyelets. After completion of the lacing operation the clamp members release the laced upper and the machine comes to rest with the lacings progressively increasing or decreasing in length, or all of the same length, according to previous manual adjustments. Lacings of increasing length are shown in FIG. 17.

Each lacing unit has mounted within it, besides the hook needle, indicated at 12, and the looper at 14, a cord end gripper and cutter comprising a pivoted jaw 16 (see FIG. 13) and a reciprocating hook 17 mounted on a slide 18, shown more fully in FIGS. 4 to 7, inclusive, to secure each cord end while forming an initial loop in a lacing. The needles are reciprocated in unison vertically to en-chain the loops of the lacing cords. As thus far described the machine of the present invention is similar to that of Patent No. 2,056,961.

Due to the crowded space in the machine of Patent No. 2,056,961 surrounding the instrumentalities for forming the lacings difficulties have been encountered because of improper operation with the result that the lacing cords have become caught on the needle hooks, stranded or otherwise entangled with operating parts of the machine and broken, especially where the lacing units have been shifted together for closely spaced eyelets in an upper. Also, in the machine of Patent No. 2,056,961 separate additional hooks are provided for disengaging from the needles each loop of cord formed by a looper and for holding that loop without proper tensional control in such position that the needle may fail to reenter that loop after being disengaged. The exactitude required to disengage each loop of cord and to hold it aside for subsequent re-entry of a needle in this way is not only a severe problem but renders proper adjustment of the machine beyond the skill and ability of an ordinary repair man, especially after slight defects in construction of the machine are encountered.

To avoid the necessity of disengaging in slack condition and holding each loop of cord for needle reentry, as in the 2,056,961 machine, the present machine has its needles arranged to retain the cord of each loop under suitable tension from the time of first engagement with a needle until the next succeeding loop of cord is re-tracted through the first engaged loop. For instance, FIG. 35 shows a shoe upper 5 with one pair of its eyelets impaled by a needle 12 before a cord is laid in the needle

hook by the looper 14. The cord carried by an eye in the looper 14 then is bent about the shank of the needle, as in FIG. 36, so that when the needle descends the main initial loop 1 is formed and retracted through a pair of superposed eyelets. After the machine starts and before each needle descends to initiate its first reciprocation the upper is gripped securely by the clamp members, indicated at 19 and 20. After descent of the needles the upper is moved forwardly to bring it out of the paths of the needles, as shown in FIG. 37. At this time the amounts of cord required for each complete lacing are drawn through tensioning devices from individual sources of supply, illustrated at 21 in FIGS. 1 and 2.

As the needle of each unit rises after its downward stroke during its first reciprocation the initial loop is held in surrounding relation to the needle, the needle rising freely through the initial loop without carrying that loop with it, as in FIG. 39. At this time both legs of the initial loop extend through the eyelets and are deflected by the forward movement of the upper, one leg running beneath the cord end gripper jaw 16 and the other leg extending through the looper 14 to the respective supply 21. When the needle has reached the top of its next rising stroke a vertically sliding fork 22 (FIG. 24) on the looper is depressed and surrounds the gripper held leg, indicated at 23, of the initial loop 1 to press it against the right side of the needle (FIGS. 38 and 39) as shown by the broken line position of FIG. 38. The needle then starts the descent of its second stroke, the gripper held leg 23 of the initial loop being laid into the throat of that needle hook by the fork 22 and being retracted by the needle hook through the initial loop (FIG. 40). In a similar manner the needle retracts each new loop formed by it through a previous one until a knot provided by nonslippling engage-ment of successively enchain loops is achieved.

To prevent each loop of cord held by a needle, while retracting the succeeding loop through it, from slipping so far down on the needle as to obstruct retraction of the succeeding loop a horizontal deflecting bar 24 (FIGS. 1, 33 and 34) is yieldingly mounted directly in front of and close to the needles 12. The bar 24 supports the loops above the positions they might otherwise occupy while the needles descend, thus reducing the tendency of the cords to bind on the needles. For this purpose the right end of the bar 24 is secured to an arm 26 pivotally mounted at 28 on a right side frame 30 for the machine, a spring 32 being stretched between pins 34 on the frame and the arm. To retain the bar in operative position its upward movement is limited by the engagement of the arm 26 with a stop screw 36 passing through a bracket 38 on the side frame 30.

Not only does the machine of the present invention avoid the difficulties encountered from disengaging each loop of lacing cord from a needle hook and again reentering the same loop with reliability but the elimination of a separate loop disengaging hook acting on the needle within the already crowded space surrounding the needle assists greatly in simplifying the expensive construction and diffi-culties in maintenance of the machine shown in Patent No. 2,056,961.

To provide still further assurance that no entanglement of lacing cords or improper release of cord loops from needles will occur in the present machine, the needles 12 are mounted for both reciprocatory and simultaneous ro-tary movement about their lengthwise axes. To enable both reciprocatory and rotary movement two sets of mechanisms are provided, one set for each movement. Thus, each needle is turned from one angular position most convenient for laying the cord in its hook, into another angular position while the loop formed during the downward stroke of the needle is being retracted through a previously formed loop surrounding the needle, and to a third angular position while each needle is at the lowermost position in its descending stroke to tighten the enchain loops progressively as each loop is retracted,

to reposition the loop so that it surrounds the needle shank and to withdraw a measured amount of cord in advance of a lacing operation without danger of overstraining the needles by deflection or of other improper cord handling. In this way a much more reliable control of the cords in each lacing operation is possible without the necessity of additional cord handling instrumentalities in the crowded spaces about the needle hooks.

Reference to FIG. 12 of the drawings will illustrate the rotary movements imparted to the needles. In this figure three angular positions, in which the needles are simultaneously oriented, marked "Forward," "90°" and "Rearward" are shown. In their Forward positions (FIG. 14) the hooks of the needles face toward the front of the machine, also when the machine is stopped, ready for application of an upper to the needles and loops carried by the needles are most effectively retracted past the legs and through the bights of previously formed loops. In the 90° positions the cords may effectively be laid by the loopers in the throats beneath the needle hooks. In their Rearward positions the needles face with their open hooks disposed to the rear of the machine, the loops carried by them being drawn into encircling relation to the needle shanks and most readily tightened while the needles are in their lowermost positions, especially to withdrawn proper amounts of measured cord from the supplies 21 by a take-up 40, acting on the cords between the loopers and the tensioning devices, comprising a set of disks 42 (FIGS. 1, 2, 25, 26 and 27). Also in their 90° positions the needle hooks face to the right side of the machine, looking from the front, as in FIG. 13, the gripper legs 23 also being most readily laid in each needle hook by the sliding fork 22 on the looper, as shown in FIGS. 38 and 39.

The advantages gained in rotating the needle from the 90° position, shown in FIG. 13, to the forward position, shown in FIG. 14, is readily apparent from an examination of these figures. This is because the loopers 14 act most easily in laying the cords in the throats beneath the hooks, shown at 44, while the hooks face in the 90° position. When the looped needles start to descend they are rotated to a Forward position to prevent their hooks from stranding the gripper held legs 23 of the initial cord loops 1.

Turning again to FIG. 12 it will be seen that when the machine is in stopped position (FIG. 35) the needle is held in its Forward position with its hook facing the front of the machine. The outline A in FIG. 12 illustrates each needle position by a pointed portion showing how the hook 44 is oriented and the parenthetical number (35) indicates the corresponding figure of the drawings in which this position of the needle is actually shown. Each positional figure also is identified with a capital letter corresponding to a needle outline designation of FIG. 12.

As soon as each needle starts to descend with an initial loop 1 of lacing cord it is rotated to bring its hook into a Rearward position B, as in FIG. 37, a measured amount of cord for each lacing having been drawn through the tension disks 42 from the supplies 21 as the upper 5 is carried forwardly out of the paths of the needles. In this Rearward position of each needle hook the bight of the initial loop 1 is drawn downwardly from the loop supporting bar 24 into surrounding relation to the needle shank to prevent disengagement from the needle, as well as undue flexure of the needles from pull of the cords toward the front of the machine. As the needles rise they are rotated from their Rearward positions to a 90° position C (FIG. 39) where the vertically sliding fork 22 on the looper engages the gripper held leg 23 of the initial loop 1 with the needle. As the needle descends with the second loop 7 of cord (FIG. 40) the needle is rotated to the Forward position D to avoid entanglement with the bight of the initial loop. From the position D the needle rotates to the position E with its hook 44 Rearward, as in FIG. 41, to prevent escape of the loop 7 from the hook when the cord is tightened. Thereafter, the

needle rises and rotates again to its intermediate 90° position F, as in FIG. 42, to enable the cord in the supply leg of the initial loop to be laid into the hook, as in FIG. 43. Upon descent of the needle it is rotated to the Forward position G to prevent its hook from stranding the gripper leg 23 of the initial loop 1 and to permit unimpeded retraction of a third loop 9 through the loop 7, as in FIG. 44. As the needle descends to its lowermost position it is rotated to its Rearward position H while the third loop 9 is being tensioned (FIG. 45), returning to its 90° position I to receive within its hook the gripper held leg 23 of the initial loop by the action of the fork 22, as in FIG. 46, for the formation of the fourth and final loop 11. After laying the cord into the needle hook for the formation of the final loop 11 the needle descends to retract that loop through the loop 9, the needle again being turned to its Forward position J to enable unimpeded passage through the loop 9, as shown in FIG. 47. As each final loop 11 is completed the needle remains in its Forward position J, a tensioning movement of the take-up acting on the cords running to the tension disks 42 to tighten each third loop 9 against the final formed loop 11.

After each final loop 11 is formed (FIG. 47) the gripper hook 17, having advanced to surround the supply end of the lacing being formed, releases the initial end of the cord in that lacing, so that there is no need to rotate the needle further. After releasing the end of each final loop 11 in the lacing the hook 17 retracts, drawing with it a portion of cord running between the looper 14 and the loop 11 while the needle still engages that loop and tightening further the loop 9 in its embrace of the final loop 11.

At the end of its final retracting movement each hook 17 wedges the cord running from the looper 14 beneath the gripper jaw 16 and presses the cord against a sharpened forward edge 46 (FIG. 48) of the slide 18 to sever the cord running to the final loop 11 of the completed lacing. At the same time the needle 12 of each unit rises to its highest position with its hook still facing the front of the machine, as in FIG. 48, and the final loop 11 drops off the needle hook, so that the completely laced upper is freed for release from the machine when the upper clamp disengages it.

For the purpose of securing accurate formation of lacings with uniformly measured lengths along the eyeleted edges of each upper operated upon, so that it may be opened up for application to the last about which it is to be stretched, each lacing unit has a cord measuring finger 48 mounted on an individual frame separate from a main stationary frame for the machine, the main frame having besides the right side plate 30, a base plate 50 and a left side plate 52, through which side plates there extend in horizontal positions two vertically spaced guide bars 54 clamped at their ends by nuts 55 to side plates (see FIG. 19). The guide bars pass loosely through openings in four sets of lacing unit frames consisting of four pairs of parallel panels 56, between each pair of which are fixed spacing blocks 58 (see FIG. 15).

To mount each cord measuring finger on the individual frames the spacing blocks 58 each have rotatably mounted in them a horizontal bearing pivot 60 projecting from the front of each block (FIGS. 14 and 29). The projecting end of each pivot 60 has a slotted enlarged head 65 through a perforation of which passes a pin 62 (FIG. 15) for holding within the slot the lower portion of a cord measuring finger 48. To hold each pivot 60 from lengthwise displacement its rearward end is threaded at 64 (see FIG. 29) within a correspondingly threaded bore in the block 58. The upper end of each finger 48 has a right angle cord engaging flange 66 (FIGS. 13 and 14) for determining the amount of slack in a completed lacing, the cords being carried over and around each measuring finger during formation of the initial loop 1 in each lacing.

To shift the lacing units toward and away from each other, so that uppers having differently spaced eyelets may be laced effectively, one individual lacing frame, 56, 56 (see FIG. 16) at the left side of the machine is secured in fixed position against the adjacent side plate 52. Three other frames 56, 56 are moved along their guide bars 54 equal distances away from each other and from the stationary frame by three sets of parallel links 68, 70 and 72 pivotally connected between the three frames and horizontal arms 74, 76 and 78, the latter two of which comprise parts of bell cranks, one being fulcrumed on a bolt 80 screwed into the base 50 of the main frame and the other being made fast to a shaft 82 just above the base 50. The shaft 82 has its lower end rotatable in the main frame base and its upper end is rotatable in a bracket 84 (also see FIGS. 2 and 3) projecting from the left side plate 52. Beneath the bracket 84 the shaft 82 has secured to it a spacing handle 86 by which the lacing units may be shifted in any manner required. To actuate the bell cranks comprising the arms 76 and 78, the bell cranks are connected for simultaneous rotation by a link 87.

Movements in two directions are imparted to each cord measuring finger 48, one movement being laterally from right to left in facing the machine, as in FIG. 2, to release the lacings at the end of an operation. The lacing releasing position is illustrated by dotted lines in FIG. 15. The other movement is toward and from the front of the machine to bring the fingers into the proper operative position with the upper as it is moved forwardly in its clamp and to return them to the rear after the clamp has released the laced upper.

To impart the lateral movements to the cord measuring fingers 48 each pivot 60 between its slotted head and the threaded portion 64 in the spacing block 58 carries a cam 88 of trapezoidal cross section, best shown in FIGS. 4, 18 and 29. The cams 88 are surrounded by a close fitting yoke 90 extending horizontally across the front of the machine and supported by studs 92 rotatable at the ends of arms, one 94 (FIG. 19) at the right side of the machine frame and the other on a lever 96 (FIG. 18) at the left side. The studs 92 are secured to the ends of the yoke and when the yoke is raised the cams rotate the measuring fingers to swing the flanges 66 into positions where they will engage the cords. When the yoke is lowered the cams rotate the measuring fingers out of the completed lacings to release the upper.

To bring the cord measuring fingers 48 toward and from the front of the machine an intermediate angular portion of each finger has a perforation fitting loosely about a horizontal rod 98 (FIGS. 2, 15 and 35), the ends of which rod are restrained from escape by a pair of links 100 (FIG. 35) although leaving the rod capable of limited angular movement with relation thereto. The links 100 are each pivotally connected, one at its rearward end, to an arm 102 (see FIG. 1) at the right side of the machine and to the upper arm of a lever 104 (see FIG. 3) at the left side of the machine. The arm 102 is made fast to the right end of a horizontal shaft 106 rotatably mounted in the side plates 30 and 52 of the frame and the lever 104 is similarly made fast to the left end of the shaft 106 (FIG. 3). A lower arm of the lever 104 is pivotally connected through a link 108 with a short arm 110 made fast to a horizontal rock shaft 112 rotatable in the frame side plates 30 and 52 just to the left of the left plate 52. At the right side of the right plate 30 (FIG. 11) the shaft 112 has secured to it an upstanding arm 114 carrying a roll 116 to engage with and be actuated by a cam 118 keyed to a main shaft 120, the main shaft being rotatable in uprights 122 attached to the base plate 50 of the main frame (see also FIGS. 11 and 23).

To raise or lower the yoke 90 (FIG. 18) which imparts lateral movement to the cord measuring fingers 48 the arm 94 (FIG. 19) and the lever 96 (FIG. 18) are made fast to a rock shaft 124 mounted for rotation in the frame

side plates 30 and 52 (see also FIG. 3). To the left of the side plate 52 the rearwardly extending arm of lever 96 is pivotally connected at 126 to a vertical link 128, also similarly connected to a forwardly extending arm of a lever 130 fulcrumed for rotation on a rock shaft 131 (also FIG. 11) in turn rotatable in pillow blocks 132 on the side plates 30 and 52. A rearwardly extending arm of the lever 130 carries a roll 133 engaging the inner edge of a cam plate 134 (FIG. 19) secured to a cam on the main cam shaft 120.

The upper clamp member 19 (FIGS. 1, 2, 30 and 51) comprises a rectangular bar loosely connected at its ends for individual movements toward and from upper clamping position. The left end is attached by a shoulder screw 136 (FIG. 30) to an arm 138, the screw engaging an enlarged opening 140 in the arm and the screw being threaded rigidly within the clamping bar. The arm 138 is made fast to a hub 142 mounted for rotation on a spindle 144 projecting from a slide 146 (see also FIG. 3) confined by a horizontal guideway 147 on the left side plate 52.

At its right end the clamp bar member 19 has a slot 148 (FIGS. 30 and 51) through which passes a bolt 150 slidably engaged with the clamp member in the slot and secured in an arm 152 made fast to a hub 154 mounted for rotation on a spindle 156 projecting from a slide 158 (see also FIG. 11). The slide 158 is confined in a horizontal guideway 160 on the right side plate 30.

To hold the clamp member 19 in raised position, so that the eyelets of an upper may be impaled by the needles, a pair of tension springs 162 and 164 (FIG. 30) are stretched between pins 166 on the arms 138 and 152, respectively, on the one hand, and pins 168 on a pair of braces 170 on the slides 146 and 158, respectively, on the other hand (see also FIGS. 3 and 11). The springs are sufficiently strong to raise the arms and clamp member 19 to the positions of FIG. 11 at the end of a lacing operation after the arms are released.

To hold the clamp bar member 19 in clamping position against the action of the springs 162 and 164 during lacing operations the arms 138 and 152 are engaged by a pair of latches 172 and 174 (FIGS. 2, 3 and 51), the latches being secured to rotating rods 176 mounted in slotted bearing blocks 178 (FIGS. 1 and 3) attached to the slides 146 and 158. Surrounding the rearward ends of the rods 176 is another set of bearing blocks 179 on the frame plates 52 and 30 of the machine. The rods 176 move in the bearing blocks 179 to shift the latches 172 and 174 with the arms 138 and 152, the latches 172 and 174 being held within the slots of the blocks 178 while the rearward ends of the rods slide lengthwise in the bearing blocks 179.

To urge the latches 172 and 174 into latching positions the rods 176 have fixed to them downwardly extending arms 180 (see also FIG. 51), between which arms and a pair of pins 182 carried by the guideways 147 are stretched a pair of springs 184. The tensions of the springs 184 serve to maintain the latches 172 and 174 at all times in engagement with the respective clamp arms 138 and 152 and to cause the latches to lock the clamp arms when lowered.

To release a laced upper from the clamp member 19 the latch carrying rods 176 have secured to them collars 186 (see FIGS. 3, 11 and 51), from which project pins 188 extending beneath a pair of latch releasing arms 190 (see also FIG. 9). The arms 190 are fixed to the ends of a transverse shaft 192 passing through bearings in the pillow blocks 132. To the left of the right side plate 30 (FIG. 8) a third, rearwardly extending arm 193 is attached to the same shaft 192 (also FIG. 3), so that when the arm 193 is actuated the arms 190 release the latches by downward movement against the pins 188. For this purpose the third arm 193 carries a roll 194 (FIG. 11) disposed in the path of a cam plate 195 attached to the left side of the cam 118.

To grip an upper securely before the needles disengage the eyelets the lower clamp members 20, of which there are five separately movable elements, are forced upwardly after the machine starts. Each member 20 consists of a headed spring pressed plunger slidably mounted in a pair of horizontal bars 196 and 198 (FIG. 2) connected together by two vertical posts 200 and 202. Between the bars 196 and 198 on each plunger is a compression spring 204 acting at its upper end on a shoulder forming a squared section of the plunger and at its lower end on the bar 198 (see FIG. 35). There is a square opening in the bar 196 for the squared section of each plunger to keep the plungers from turning.

As the lacing operations on an upper are nearing completion all of the plungers comprising the lower clamp members 20 are depressed a short distance to relieve the gripping pressures on the upper of a shoe and to enable it to drop out of the machine more easily when the clamp member 19 swings upwardly to release it. For this purpose the lower ends of the plungers extend through a pressure relief plate 206 below the bar 198. The lower ends of the plungers have threaded openings to receive fillister head screws 207 which are engaged with the under surface of the plate 206. When the plate 206 is depressed the plungers are lowered together while leaving them free for individual yielding action when engaged by the shoe upper.

For depressing the plate 206 it extends laterally beyond the ends of the bar 198 and above the ends of the plate are two arms 208 and 210 (FIG. 2). The arms 208 and 210 are keyed to a rock shaft 211 (FIGS. 3 and 11) rotating in bearings in the pillow blocks 132. Between the pillow blocks 132 the shaft also has keyed to it an arm 212 (FIG. 11) at the rearward end of which is a roll 214 disposed in the path of a cam plate 216 (see also FIG. 23) secured to a cam 218 carried by the main shaft 120. As the machine reaches its stopped position (FIGS. 1 and 11) the plunger members 20 are held in lowered positions ready for a new unlaced upper to be applied and held in place by movement of the upper clamp member 19 into its latched position from broken line to solid line position of FIG. 4. Soon after the machine starts the arms 208 release the bar 206 and the new upper is gripped securely by the clamp members.

To move the upper clamp member 19 downwardly into its latched position its ends have attached to them a pair of upwardly curved handles 220 (FIG. 2). For best results it is necessary for pressure to be exerted on both handles in order to latch both ends of the clamp bar, especially against the resistance offered by a heavy stiff upper. For this reason an operator may form the habit of applying pressure on both handles simultaneously with both hands, thereby removing his hands from any other parts of the machine before it is started. This arrangement is a safety feature tending to prevent injury to the operator.

To move the clamp members 19 and 20 forwardly from positions in which an upper is aligned with the needles, to bring the upper out of the reciprocating paths of the needles, as illustrated by the broken lines in FIG. 30, and to afford measurement of cords for the lacings, the bar 196 (FIG. 2) in which the lower clamp members 20 are mounted is loosely supported by downwardly bent ends of the slides 146 and 158 (FIGS. 30 and 51). At its left end the bar 196 (FIG. 51) has an opening through which the upper end of a screw 222 passes loosely into threaded engagement with the forward end of the slide 146 (see also FIG. 3) which lies beneath the bar 196. At its right end the bar 196 is slotted at 224 (FIG. 51) to receive a head on a shoulder screw 226 (FIG. 51) threaded into an offset in the underlying end of the slide 158. The arms 138 and 152 by which the upper clamp bar member 19 is carried, being rotatable on spindles 144 and 156 projecting from the slides 146 and 158, enabling the clamp member both to be

moved forwardly or rearwardly together while clamping an upper.

To move the slides 138 and 152 forwardly or rearwardly the rock shaft 112 (FIGS. 3 and 11) extends through the side plates 30 and 52 and at both ends the rock shaft has an arcuate two-part arm 228, 230 comprising two separate adjustable sets of connections. The part 228 of each arm, as shown in FIGS. 1, 3 and 11, comprises a plate with an arcuate slot 229, and the part 230 a plate with a series of index holes 231, between which plates is disposed a flanged head on a sleeve within which is mounted a spring pressed index pin 232 having a handle portion 233 exposed for manipulation to select a desired index hole position. The two parts of each arm are bolted together through suitable spacers and the sleeve head is confined loosely between the parts, the sleeve also passing through a forked lower end of a link 234, so that the sleeve forms a pivotal connection between the link and the two-part arm. The upper end of each link 234 is pivoted to a short arm of a lever 236 fulcrumed on the shaft 211 and a long arm of the same lever is connected through a link 238 to the slide 146 or 158 as may be. By the sets of adjustable connections assigned the cam 118 with its roll 116 and follower arm 114 actuate the forward and rearward movements of both the cord measuring fingers 48 and the clamp carrying slides 146 and 158, the movements of the clamp slides being adjustable individually in accordance with requirements.

When the cord measuring fingers 48 are in their rearward inactive positions the center of the arcuate slot in the arm part 230 lies concentric with the pivot between the link 234 and the short arm of the lever 236, so that as the lower end of the link 234 is moved along the slot in the arm 230 no relative motion will be imparted to the slides 138 and 152. To hold the levers 236 with freedom of rotation on the shaft 211 each end of the shaft has pinned to it a collar 239 (see FIGS. 1 and 3). If the pins 232 are adjusted to engage the same positions in their index plate parts 230 at the left of the machine as at the right side, then the same motion will be imparted to the left hand slide 146 as to the right slide 158. In this way the amount of slack formed between the eyelets and the measuring fingers 48 in all the lacings inserted in a shoe upper will be of the same length, the amount of slack being determined by the positions of the two pins 232.

If it is desired to provide a graded amount of slack in the lacings inserted by the machine from the inner ends of the eyeleted edges to the outer ends, then a different adjustment is made in one of the index positions of a pin 232. With a different adjustment of an index pin 232 a different movement will be imparted to one of the slides and the eyeleted edges of a clamped upper will be moved to an angular relation to the front of the machine to cause the fingers 48 at one end of the eyeleted edges to measure more cord than at the other end, as illustrated in FIG. 17.

To impart vertical reciprocating movements to the needles they are clamped to the upper ends of a series of parallel bars 240, slidably and rotatably mounted in individual angle plates 242 attached to the front edges of the spacing blocks 58 forming the frames of the lacing units, as shown in FIGS. 15 and 29. Projecting from the lower end of each needle bar 240 is a threaded stud 244 passing loosely through a slot 245 in a carrier bar 246, best shown in FIG. 2, the lower end of each needle bar resting on the carrier bar 246. At its ends the carrier bar has fixed to it a pair of dowels 248. The dowels 248 enter circular openings in a pair of blocks 250 (see also FIG. 28). The blocks 250 have projecting from each of them a pin 252 sliding in a passageway in the forward ends of an arm 254 (FIG. 3) at the left side of the machine frame and of an arm of a lever 256 (FIG. 28) at the right side of the machine frame, both the arm 254 and lever 256 being made fast to a shaft 257 rotat-

ing in outboard bearings 258 (FIGS. 1 and 3) secured to the base plate 50. The rearward arm of the lever 256 carries a roll 259 engaging a cam 260 (see FIG. 28) keyed to the main shaft (see also FIG. 23). When the carrier bar 246 is lowered check nuts 261 on the studs 244 draw the needle bars downwardly and when the carrier bar 246 is raised it raises the needle bars by engagement of their lower ends.

To rotate each needle its bar 240 is surrounded about its midlength area by an elongated pinion 262 made fast to the bar. Each pinion 262 is engaged on its right by a rack 264, the teeth of which mesh with those of the pinion. The racks are guided at their forward ends within a slot of a strap 266 (see FIG. 2) fixed at its ends to the main frame side plates 30 and 52. Along their central portions the racks are guided within bearing grooves in the spacing blocks 58 of each lacing unit. The rearward ends of the racks 264 pass loosely through a slot in a yoke 268 (see FIG. 28) running horizontally behind the lacing units and having its ends rotatably mounted in blocks 269 slidably disposed in slots of downwardly extending arms 270 made fast to the shaft 131. Also extending downwardly from the shaft 131 is an arm 272 carrying a roll 273 engaging a cam 274 (see also FIG. 23) keyed to the main shaft 120.

The purpose of the slotted bars 206 and 246, the slotted strap 266 and the yokes 268 and 90 is to allow relative spacing movements of the lacing units without disturbing the actuation of the instrumentalities in the units. The operating mechanisms for other instrumentalities in the units are similarly connected to their cam actuated parts, as will appear.

For actuating the cord end gripper and cutter devices the mechanisms shown in FIGS. 4, 28 and 29 are provided. The gripper and cutter devices are entirely actuated by reciprocating movements of each hook 17. To grip and secured the leading end of each cord it is carried by the hook beneath the pivoted jaw 16, which is pressed by a leaf spring 276 (FIG. 4) against the hook 17. The jaw 16 is pivoted on a pin 278 on a pair of ears 280 extending upwardly from the slide 18, the hook being guided at its forward end between the ears 280 and being held in firm engagement with the slide by the pressure of the jaw 16 under the force of the spring 276. Along intermediate portions the hook 17 and slide 18 are guided within a rectangular opening 277 in the spacing blocks 58 of the individual units (see FIG. 15).

At its rearward end each hook 17 has screwed to it a tongue 282 passing loosely through a slot in a transverse bar 284 extending between frame plates 30 and 52 and into an integral connection with a block 286. The block 286 has a sliding engagement with a plunger 288 having a rectangular head attached to the underside of the slide 18. On the plunger 288 is a compression spring 290 acting between the block 286 and the head of the plunger 288 in a direction tending to move the slide 18 forwardly. To prevent each spring 290 from expanding each block 286 has a pair of upstanding ears carrying a pin 292, on which is pivoted a latch 294 acting against the rear edge of the bar 284 to press it against the end of the hook 17, thus connecting each hook and slide in fixed relative positions so that when the bar is moved all of the hooks are moved correspondingly.

The ends of the transverse bar 284 are formed in the shape of dowels, one of which is shown at 296 in FIG. 28, fitting perforations in a pair of slide blocks 298 (FIGS. 28 and 29). The blocks 298 are retained between forked ends of a pair of vertical arms 300 rotatable freely on the shaft 131.

To actuate the arms 300 together, so that all of the 70 cord end grippers and cutters will move by the same amounts, the arms are secured to a brace 302 (FIG. 29), the central portion of which has screwed to it a pivot bracket 304. Pivoted connected to the bracket 304 is a link 306 also similarly connected to the upper end of

an arm 308 provided with an offset portion carrying a roll 310. The roll 310 engages a cam 312 (see also FIG. 23) keyed on the main shaft 120 and the arm swings on the shaft 257.

To enable manual actuation of the cord end grippers 16, 17 individually to be opened up for easy reception of each cord end in preparing the machine for initial operation, according to the illustrated machine, the mechanism for actuating the grippers is provided with disconnectable connections. For this purpose there is mounted just below the slides 18 a lateral rail 314 in a position to be engaged by the heads of the plungers 288, as shown in FIG. 4. While the machine is in stopped position any individual gripper may be actuated by disengaging its actuating connections comprising the corresponding latch 294 and the bar 284 and at the same time by pressing that latch with its mounting block forwardly against the force of the spring 290 the plunger 288 is moved against rail 314. Engagement of the plunger with the rail 314 causes the slide 18 to which the head is attached to be stopped, so that the particular latch 294 clears the bar 284 and the slide 18 may be pressed further in a forward direction. Further forward movement of the latch then presses the hook 17 connected with the latch mounting block 286 against the spring 290, compressing it without moving the slide 18. In so doing the hook 17 moves out beyond the jaw 16 to enable a length of cord to be presented to it, whereupon release of forward pressure on the latch permits the spring 290 to expand and the hook to draw the cord in the hook 17 into firm gripping engagement with the jaw 16. If there is any excess length of cord on the end presented to the hook at this time the excess will be trimmed off by the sharpened edge 46 on the slide 18, so that there is no danger of entanglement between excessive lengths of cord ends with the other cords or with the operating parts of the machine.

To assist in selecting a latch 294 for the desired cord gripper actuating connection all the latches have angular handle portions 315 each of graded height relatively to the others. In this way the highest latch end 315 will operate the left hand gripper and the shorter latches will act progressively to operate those at the right. To relatch the latches 294, each has a compression spring 316 (FIG. 4) mounted between its angular end and the block 286. After releasing a latch 294 as the hook 17 to which it is attached is moved rearwardly by the spring 290 the bar 284 will be relatched by the spring 316.

To prevent release of cord ends from the grippers 16, 17 during normal operation of the machine or when the machine is stopped in a position other than its normal stop position, the rail 314 is fixed to the forward end of an arm 318 having an elongated hub 320 freely rotatable on the shaft 192, as shown in FIG. 4. Also attached to the rail 314 is a lug 322 through which passes a pin 324 to form a pivotal connection with an upper end of a link 326. The lower end of the link 326 is pivotally connected to an arm 328 secured to the shaft 112, to which also is secured the arm 114 (FIG. 11) carrying the cam roll 116 for actuating the cord measuring fingers 48 toward and from the front of the machine. The forward movement of each measuring finger 48 takes place in the first part of the machine operation and the reverse movement takes place at the last part of the operation. Accordingly, the rail 314 is lowered from its highest position where it will be engaged by the head of the plungers as soon as the machine starts in operation and is not restored until the operation is nearly completed. Thus, the grippers may not be opened manually except when the machine is in normal stopped position.

To determine proper measurement of cords withdrawn from the supplies 21 after each initial loop 1 of cord has been drawn through an eyelet in the upper of a shoe, so that no substantial amount further needs to be withdrawn by the lacing and knot tying instrumentalities during a lacing operation, thereby avoiding irregularities common

to withdrawal of cord from bulky supply holders, the braces 170 on the slides 146 and 158 (see FIGS. 30, 31 and 32) are bent at their upper ends toward each other and have threaded into them shoulder screws 330. The screws 330 pass through slots 332 in a measuring beam 334 having a series of guide eyes 336 spaced along its length between the screws 330.

The paths assumed by the cords for the lacing units between the supplies 21 and the loopers 14 extend through individual guide tubes 338 (see FIGS. 1, 2, 3 and 25), the tension disks 42, the guide eyes 336 (FIG. 30) in the beam 334, beneath a rod 340, upwardly to individual perforations in a cross bar connecting the arms of the take-up 40 and downwardly to an opening in a reversely bent spring 342 for each cord just before the cords enter the eyes of the loopers 14, the springs 342 being attached to the looper bars, as shown in FIGS. 4 and 15.

In measuring cords the paths taken by them between the tension disks 42 and the loopers 14 increase or decrease in amounts as the measuring beam 334 moves rearwardly and forwardly, as shown in FIG. 25. Since both ends of the beam are connected by the screws 330 to the braces 170 on the slides 146 and 158 and the clamp members 19 and 20 are mounted on the same slides the amounts of cord suspended between the tension disks 42 and the loopers 14 will be decreased two to one as the slides move in a forward direction with the measuring beam 334, the beam acting as a pulley to give up cord (see FIG. 25). However, at the time the slides 146 and 158 move forwardly the upper 5 is securely clamped by the clamp members and drawn forwardly to increase the amounts of cord between the loopers 14 and the cord grippers 16, 17, as shown in FIG. 37, at a rate of four to one, thus resulting in net increases of two to one in the amounts in cord suspended between the tension disks 42 and the grippers 16, 17 for forward movements of the slides. The net increases in amounts of cord of two to one are exactly enough to meet the requirements for each lacing, since each completed lacing is composed of two legs in its initial loop 1, as shown in FIG. 17.

The overall withdrawal of cords for each lacing is accomplished by the take-up 40 which, at the time the clamped upper is moved forwardly, as in FIGS. 3 and 37, is in its greatest cord retracting position. For this reason almost all of the cord required to complete a series of lacings is withdrawn from the respective supplies before the knots in the lacings have their first and second loops enchain. In this way adequate amounts of cord are provided for completing each lacing without necessitating withdrawal of more than very short lengths of cord from the supplies during the formation of the knots. Thus, any irregularity in tension caused by inertia of supply spools or formation of kinks between supply spools and the tension disks 42 will be minimized.

The overall measurement of cord amounts at the beginning of a lacing operation is not only provided in direct proportion to the forward movement of the upper after the initial loops 1 have been withdrawn through the eyelets by the needles but when the positions of the index pins 232 are adjusted differently to provide graded amounts of slack in successive lacings then, because of the angular position assumed by a clamped upper after the formation of the initial loop 1, the exact amount of cord will still be measured for lacing each pair of superposed eyelets.

The construction of each looper 14 is best shown in FIGS. 4, 15 and 24. Each looper is in the form of a bar clamped to the forward end of a horizontal rod 344 slidably and rotatably mounted in each block 58 in an individual lacing frame. The lower end of each bar of the looper 14 has a forwardly projecting lug provided with an eye 346 (FIGS. 13 and 14), through which the lacing cord is guided. At the rear of the looper bar the fork 22 (FIG. 24) is guided for vertical movement between the looper bar and a collar 348 (FIG. 4) clamped to the rod 344 and has a pair of hook shaped prongs 350 (FIG. 24) embrac-

ing the looper bar, the sides of the looper bar being recessed to receive the prongs. To permit the fork 22 to move on the looper bar the upper end of each fork 22 has a slot 352 of sufficient width to clear the rod 344.

To actuate each looper 14 the rod 344 to which its bar is clamped is reciprocated for forward and rearward movement and rotated for lateral movement to actuate its eye 346 in an arcuate path about the hook end of an associated needle 12. To reciprocate the rods 344 the rearward end of each is reduced in diameter and is confined within a slot 354 (see also FIG. 20) in a carrier bar 356, the reduced end of each rod 344 having clamped to it a collar 358 (FIG. 4) to prevent escape of the rod. At the ends of the carrier bar 356 are formed trunnions entering perforations in two rectangular slides 360 (FIG. 21) guided within forks at the upper ends of a pair of arms 361 secured to a shaft 362 (FIG. 19). The shaft 362 is mounted for rotation in the pillow blocks 132 and has keyed to it an arm 364 carrying a roll 366, bearing against a cam 368 made fast to the main shaft 120.

To rotate the looper supporting rods 344 each rod has fixed to it an arm 370 (FIGS. 4 and 22). At the upper end of each arm 370 is a pin 372 entering a slot 374 in carrier bar 376 formed with trunnions at its ends. The trunnions at the ends of the bar 376 are rotatable, one at the right side of the machine in an arm 378 and one at the left side of the machine in an arm of a lever 380 (see FIGS. 3 and 19). The arm 378 and lever 380 are made fast to the ends of a shaft 382 supported for rotation in projections 384 (FIGS. 1 and 3) from the main frame side plates 30 and 52. A rearwardly extending arm of the lever 380 has a roll 386 engaging the cam 218 (FIGS. 19 and 23).

To enable each fork 22 to be depressed in the direction of the arrow and to surround the gripper held leg 23 of the loop 1 while leaving the looper 14 free to move laterally as each rod 344 is rotated, each fork 22 has attached to its rearward side a headed stud 388 (see FIG. 24). The head of each stud 388 is slidably mounted in a horizontal T-shaped slot 390 (FIG. 4) in an enlarged forward end of a staff 392 (see also FIGS. 8 and 19) guided for vertical movement within a confined space between the individual frame panels 56 of each lacing unit. At its rearward end each staff 392 has a pair of aligned slots 394 and 396 (FIG. 4). The slots 394 have passing through them a rod 398 (see also FIG. 8) the ends of which are rotatable in bearings in the side plates 30 and 52 of the main frame. Between the side plates 30 and 52 on the rod 398 is clamped one end of an arm 400 (FIG. 19) for rotating the rod 398. Also between the side plates on the rod 398 are clamped two supporting arms 402, one close to each side plate 30 or 52. The supporting arms 402 have rearwardly extending ends carrying between them a pin 404 passing through the slots 396 (see also FIG. 4) in the staffs 392, so that the forward ends of the staffs may be raised or lowered together without interfering with the forward or rearward movements of the staffs as the looper carrier bar 356 is reciprocated. The lateral shifting movements of the loopers 14 also is not impeded by the connections with the forks 22, the headed studs 388 sliding in the T-shaped slots 390 in the forward ends of the staffs 392.

To actuate the arm 400 (FIG. 19) for rotating the fork depressing rod 398, the arm 400 has a slotted rearward end through which passes a peg 406 projecting from a C-shaped arm of a lever 408. The lever 408 is fulcrumed loosely on the shaft 192 at the right of the machine and an arm of the lever 408 carries a roll 410 engaging a cam 412 on the main shaft 120.

To enable actuation of the take-up 40 in its movements of taking up and giving up cord in accordance with the requirements of the other cord handling instrumentalities it is mounted to rotate loosely on the shaft 382 (FIG. 25). The perforations in the cross bar of the take-up 40 provide selective guides for the cords in accordance with the

spacings of the lacing units and the tensions desired in the formation of the several lacings. Connected to the ends of the cross bar are a pair of arcuate arms 414 (see FIGS. 2, 3 and 25). The arms 414 are integrally joined at their lower ends to a U-shaped yoke 416 having openings for the shaft 382, one arm of the yoke being longer than the other and extending below the shaft. The longer arm of the take-up yoke is shown best in FIG. 3 and is pivotally connected by a link 418 (also FIG. 25) to the upper end of a lever 420 fulcrumed loosely on the shaft 257, the central part of the lever carrying a roll 422 engaging a cam 424 on the main shaft 120. The cam 424 is also the one to which the cam plate 134 is secured.

To assist in stringing the cords through the machine preparatory to initiating operations and for other purposes, mechanism in the machine acts on the tension disks 42 to free the cords of tension when the machine stops. Tension is applied by the disks to the cords as the cords are squeezed by the disks through the action of a spring 425 (FIGS. 26 and 27) compressed between a thumb nut 426 threaded on a hollow spindle 428 supporting the disks and five spacers 430 acting against the disks, in a well known manner, to press them together. The spindle is supported by a standard 432 attached to the upper edge of the right hand frame plate 30 (FIG. 25).

To free the cords of tension the hollow spindle 428 has slidably mounted in it a pin 434 arranged with one end engaging a cross bar 436 passing through a slot in the end spacer 430 to support the pressure of a washer 438 against which the spring 425 acts to transfer the spring force to that spacer. To relieve the first spacer 430 from the force of the spring the other end of the pin 434 is engaged by one arm of a right angle lever 439 pivoted within a slot in the standard 432. When the machine is brought to rest at the end of a lacing operation an outstanding arm of the lever 439 is depressed by a forwardly projecting arm of a lever 440 (FIGS. 25 and 26) fulcrumed on the shaft 382 and provided with a roll 442 at its rearwardly extending end, the roll being engaged by a cam plate 444 on the right side of the cam 118 for this purpose.

While all of the cams on the main shaft of the machine are illustrated as being of the "open" type, as distinguished from the "closed" or grooved form of cam, it is preferred to employ "closed" type cams throughout the machine, not only to insure more reliable operation assured by such cams but also to reduce the resistance met with open cams by reason of the forces applied by springs required to hold rolls acting on the cams in proper positions at all times. Such springs are shown in the present drawings at 446 (FIG. 3), 448 (FIG. 25), 450 (FIG. 28) and 452 (FIG. 29). In other instances the springs have not been shown, either to simplify the illustration or because in a few instances no spring is required to hold a roll against a particular cam. Where no spring is employed it usually is necessary to provide motion limiting stops for cam actuated parts, particularly where the cam is in the form of a block made fast to a complete 360° disk.

To rotate the main shaft 120 a driving and stopping mechanism is provided. The driving and stopping mechanism includes a spur gear 454 (FIGS. 1 and 2) attached to the shaft 120, the teeth of which gear mesh with those of a pinion 456 having half the number of teeth as the gear. The pinion 456 is slidably mounted on a countershaft 458 but keyed to the shaft to prevent rotation thereon. A hub on the pinion has formed in it a helical wedge 460 (FIG. 23) with an abrupt shoulder at its end. Cooperating with the grooved hub on the pinion 456 is a spring pressed vertically slidable stop bolt 462 (FIGS. 1 and 2) acting when permitted to engage the wedge 460 to shift a driving end surface on the hub of the pinion 456 away from a similar surface on the hub of a pulley 464 rotatable on the countershaft 458 and to bring the countershaft abruptly to rest with the shoulder against the stop bolt, the driving surfaces of the pinion and pulley

being pressed yieldingly together during operation of the machine in a manner common to positive stop clutches.

Since the spur gear 454 and pinion 456 have a one-to-two driving ratio and it is desired always to rotate the main lacing shaft a single 360° turn the stop bolt 462 is held from rising by a latch 466 riding on a collar 468 on the stop bolt. When the stop bolt is depressed, retracting it from the wedge 460 in the hub of the pinion 456, it is locked by engagement of the latch with the collar until the second rotation of the countershaft is completed. For this purpose the latch 466, in the form of a three-armed lever fulcrumed on a pin 470 on the machine frame, is pressed yieldingly into the path of a lug 472 on the spur gear 454 by a spring 474 stretched between a rearwardly extending arm of the latch and a screw 475 on upright 122. During the first rotation of the countershaft the stop bolt 462 remains locked down but toward the end of the second rotation of the countershaft the lug 472 disengages the latch 466 from the collar on the stop bolt and the machine comes to rest.

To start the machine in operation the lower end of the stop bolt 462 is pivotally connected to a link 476 (FIG. 1) in turn similarly connected to a lever 478, through which passes a fulcrum pin 480 mounted in a bracket 481 supported beneath the base 50 of the machine. To the lever is connected an armature 482 of a solenoid 484 on the bracket 481, the solenoid being arranged when energized to retract the stop bolt from the wedge in the hub of the pinion 456 against the force of a spring 485 (FIG. 1) stretched between the lever 478 and the machine base. When the stop bolt is retracted the pinion 456 is pressed by a spring (not shown) into driving engagement with the hub of the pulley 464.

The solenoid is energized to retract the stop bolt 462 from the groove in the hub of the pinion by any suitable manually operated switch or by a conveniently located treadle. As a further safety feature and to render the control of the machine semiautomatic, according to the invention, two separate serially connected switches 486 (FIGS. 51 and 52) are located at opposite ends of the bar of the clamp member 19, which switches when actuated together complete the circuit to the solenoid 484. Because an operator must use both hands to operate the switches he must take both hands off the operating parts of the machine so that there is less chance for him to be injured by the machine.

The connections between the switches 486 are shown in FIG. 52. To reduce the electrical hazard the solenoid 484 is energized through a voltage reduction transformer 488 from a 110 v. source 490.

The use of two serially connected switches 486 is particularly desirable with the present machine where the upper clamp bar member 19 ordinarily requires two hands to move it into clamping position, downward pressure on both handles 220 being required to latch the bar member. Downward pressure on the handles is used also to close the switches 486, so that as soon as the clamp member is latched the machine is started without loss of time.

The switches 486 are actuated at closed positions by a pair of vertically sliding rods 492 guided in perforations at the upper and lower bent ends of a pair of straps 494 mounted on the side plates 30 and 52 of the machine frame. The upper ends of the rods 492 are engaged by flanges on a pair of arms 496 secured to the rods 176, so arranged that when the latches 172 and 174 move into locking engagement with the arms 138 and 152 which support the clamping member 19, the switches close their contacts. When the latches release the arms 138 and 152 the latches slide along the sides of the arms 138 and 152 in the positions shown in FIG. 51. In this way the switches are moved into and held in open circuit positions.

The time chart of FIG. 53 shows the relative motions imparted to the upper and cord handling instrumentalities

ties, the respective motions being indicated in the table below.

TIME CHART

Curve letter	Instrument	Remarks
A	Take-up 38.	The top line of the chart represents the maximum taking up movement except for a short heavy tension applied at 310° for tightening the knot after completion, the tension in the lacing cords thereafter being relaxed at the 340° position, as the upper clamp is being returned to a rearward position.
B	Cord Measuring Fingers 48 (lateral).	The horizontal reference line represents a left position out of the paths of the cords and the upper line indicates movements to the right into the paths of the cords.
C	Lower Clamp Members 20.	From a depressed starting position at the start, members 20 rise into firm gripping engagement on the upper until a 340° position is reached when the members 20 are again depressed to release the grip on the upper.
D	Loopers 14 (lateral).	The base line points indicate movements to the left and the highest points show movements to the right.
E	Needle 12 rotation...	The base line points of the needles are with their hooks facing Forward and the highest points show the hooks facing Rearward, intermediate points indicating 90° orientation.
F	Cord End Gripper and Cutter 16, 17 and 18.	Base line points are those in which the hooks 17 are drawn rearwardly and the highest points are those in which the hooks 17 are moved forwardly.
G	Needle Reciprocation.	The base line points of the needles are those where the needles are highest and the lowest points in this curve show the lower positions of the needles while they have retracted loops of cords.
H	Loopers 14 (forward & rearward).	Each looper supporting rod 344 is in a rearward position along the base line and in a forward position along the higher points of the curve.
I	Cord Forks 22 (up and down).	Base line points for the forks are those with the forks highest and the lower points show the forks lowered to engage the gripper held cord ends 23.
J	Latches for Upper Clamp Member 19.	Latches release clamp arms at 340°.
K	Clamp Slides 146 and 158 (forward and rearward) and Cord Measuring Fingers 48.	The base line shows rearward positions and the higher points the forward positions.
L	Tension Disks 42 (application and release).	The higher points indicate release of cord tension and the base line shows tension applied to the cords.

It thus appears that a shoe upper lacing machine has been provided for forming and tying a knot in a lacing of the type described, in which each loop of cord, except the final one in a lacing, is retained continuously on a hook needle from the time the cord forming that loop is laid in the needle hook until a succeeding loop is retracted through that loop by the needle without requiring a separate hook member for taking that loop from the needle hook and holding it open so that the entire needle shank may reenter that loop during its ascending stroke of the needle, as in the machine of Patent No. 2,056,961. The loops in the present machine are held on the needles under properly controlled tension because the needles have their hooks properly oriented during their ascending strokes, so that the loops slide directly along the shanks rather than off the hooks as the needles rise. In the machine of Patent No. 2,056,961 continuous engagement of the loops with the needles is impossible because each needle hook faces the front of the machine at all times and the shanks of the needles cannot enter these loops in a manner to cause successive enchainment without the use of additional instrumentalities.

The nature and scope of the invention having been indicated, what is claimed is:

1. A machine for lacing eyeleted shoe uppers having a number of reciprocating hook needles for impaling the eyelets in uppers, loopers for forming initial loops by laying cords in the hooks of the needles and for forming

knots between the legs of the initial loops and the bights of those loops after being retracted by the needles from the eyelets, said knots comprising successively enchain loops in alternate legs of the initial loops, members for clamping the upper in folded condition assumed by impaling the eyelets on the needles, sources of supply for the lacing cords, mechanism for moving the clamp members to bring the upper out of the paths of the needles to prevent their reentry a second time into the eyelets, and take-up means for withdrawing amounts of cord from the supply sources after the upper is moved out of the paths of the needles and for giving up the withdrawn amounts of cord during the formations of the knots, in combination with mechanisms for actuating the needles and the loopers to retain each loop, except the final one of a knot, on each needle from the time the cord forming that loop is laid in that needle hook until a succeeding loop is retracted through that loop.

2. A lacing machine, as in claim 1, in which there is provided mechanism for rotating the needles simultaneously with their reciprocations to prevent the loops formed by the needles from being caught by the needle hooks while successive loops are being retracted through them.

3. A lacing machine, as in claim 1, in which mechanisms are provided for rotating the needles to turn the hook of each from one angular position convenient for laying the cords into them and into another angular position while the loops so formed are being retracted through the previous loops to prevent the cord in one loop held by each needle from being caught by the needle hook while retracting a successive loop through that loop.

4. A lacing machine, as in claim 2, in which the needle rotating mechanism acts to turn each needle from one angular position with its hook facing toward the side of the machine as the cords are being laid in the needle hooks and to turn each needle into a position with its hook facing toward the front of the machine while retracting successive loops through those formed by the cords first laid in the needle hooks.

5. A lacing machine, as in claim 1, in which there are provided cord end grippers to secure the leading end of each cord while forming an initial loop in a lacing and mechanism having disconnectable connections for enabling manual actuation of the cord grippers individually to open the grippers for reception of a cord end in preparing the machine initially for operation.

6. A lacing machine, as in claim 5, in which the disconnectable connections comprise latches with handle portions of graded height to assist in selecting a latch for the desired cord gripper.

7. A lacing machine, as in claim 1, in which there are provided measuring means connected to the clamp moving mechanism for determining the amounts of cords withdrawn by the take-up from the supplies for each lacing.

8. A lacing machine, as in claim 7, in which the measuring means acts while the upper is moved out of the paths of the needles and decreases the amounts of cords measured by movement of the upper out of the paths of the needles.

9. A lacing machine, as in claim 8, in which the measuring means acts to decrease the amounts of cords measured at a rate of two to one with respect to the distance in which the upper is moved out of the paths of the needles while the actual movement of the upper out of the paths of the needles increases the amounts of cords required at a rate of four to one, leaving a net increase in amount of cord measured at a rate of two to one.

10. A lacing machine, as in claim 9, in which there are provided two sets of adjustable connections in the mechanism for moving the clamp members out of the paths of the needles to enable a graded amount of slack to be provided in the lacings from one end of the eyeleted edges of the upper to the other end.

11. A machine for lacing eyeleted shoe uppers having a needle for impaling superposed eyelets in an upper, means for actuating the needle to pass a loop formed by the needle across the edges of the upper and to form a knot between the legs of the loop and the bight of the loop, a manually actuated member for clamping the upper in folded condition assumed by impaling the eyelets on the needle, and driving and stopping mechanism for the machine, in combination with means for actuating the driving and stopping mechanism to drive the machine and to bring it to rest through manual operation of the clamp member toward clamping position.

12. A lacing machine, as in claim 11, in which the clamp member comprises a bar and arms to which the bar is loosely connected for relative movement at its ends and there are provided two separate means at opposite ends of the bar which, when actuated together, cause the driving and stopping mechanism to start the machine.

13. A lacing machine, as in claim 12, in which the means for causing the driving and stopping mechanism to start the machine comprise a stop bolt, a solenoid having an armature connected to the stop bolt, and a pair of switches actuated by opposite ends of the clamp bar, said switches being connected in series to close the circuit to the solenoid when actuated together.

14. A lacing machine, as in claim 1, in which each looper comprises a bar having a cord guiding eye mounted for forward and rearward movements and for lateral movements to carry each guiding eye about the hook end of the needle, and a cord engaging fork guided for movement along the looper bar to lay in the needle hook a leg of a loop previously laid in the needle hook by the cord guiding eye of the looper bar.

15. A lacing machine, as in claim 14, in which there is provided mechanism for actuating the looper fork along the looper bar without impeding the forward, rearward and lateral movements of the looper guide eye.

16. A lacing machine, as in claim 15, in which the mechanism for actuating each looper fork comprises a vertically movable staff having a horizontal slot and a stud on the looper fork engaging the staff within the horizontal slot.
